BEVERAGE VENDING MACHINE

John A. Greenly, Minneapolis, Minn., assignor to Norris Dispensers, Inc., Minneapolis, Minn., a corporation of Minnesota

Application December 24, 1956, Serial No. 44,314

Term of patent 14 years

(Cl. D52—3)

FIG. 1

The back of the dispensing machine is plain and unadorned, and the undisclosed side is substantially the same in appearance as the side shown in Figure 2.

I claim:

The ornamental design for a beverage vending machine, substantially as shown and described.
